Henry Bergoe

Henry Berger, of New York, N.Y.
Letters Patent No. 2134 Dated July 18 1865.
Design for a Bust of A. Lincoln.

DES. 2134

The schedule referred to in these Letters Patent and making part of the same.

To whom it may concern:

Be it known that I, Henry Berger, of the City, County and State of New York, have invented and produced a new and original design for a bust of Abraham Lincoln; and I do hereby declare the following to be a full and exact description of the same, reference being had to the annexed drawing, making a part of this specification, which said drawing represents a perspective front view of the said bust, standing on a marble shelf.

The base of the said bust consists of seven moulded members. The chest and shoulders of the bust are cut off on the lower part in the form of a segment of a circle and the same is covered by a toga gracefully draped leaving the front of the neck and a small part of the front of the chest free and uncovered.

The beard on the face is represented as covering part of the cheeks, the lower jaw and chin.

The face is represented and intended as a true likeness of the original, with all its characteristics. The hair is represented as falling on the left side and well trimmed.

The whole bust is a true and artistic representation of Abraham Lincoln, the late martyr President of the United States.

DES. 2134

The said bust may be executed either in marble, plaster, metal, or any other material suitable for that purpose.

What I claim as new and desire to secure by

Letters Patent of the U. S. is -

The design for a bust of Abraham Lincoln.

substantially as described and as represented in the associated drawing.
